MEDICAL, DENTAL AND VETERINARY IRRIGATOR AND APPLICATOR

Garrison G. Trupp, 4600 York Road, Baltimore, Md.
21212, and Marc A. Trupp, 23 Stonehenge Circle,
Pikesville, Md. 21208

Filed July 24, 1970, Ser. No. 24,107

Term of patent 14 years

Int. Cl. D24—03
U.S. Cl. D24—1

FIG. 1

FIG. 2

FIG. 3

FIG. 4

FIG. 5

FIG. 6

FIG. 8

FIG. 7

SEARCHED

FIG. 1 is a side elevational view of a medical, dental and veterinary irrigator and applicator, showing our new design, portions of the applicator being broken away for convenience of illustration.

FIG. 2 is a top plan view.

FIG. 3 is a bottom plan view.

FIG. 4 is a rear elevational view.

FIG. 5 is a front elevational view.

FIGS. 6, 7 and 8 are elevational views illustrating modified tips that can be used with the present invention.

We claim:

The ornamental design for a medical, dental and veterinary irrigator and applicator, as shown.
